PORTABLE CONCRETE MIXER

Harold A. Wagner and Gustave H. Wagner,
Portland, Oreg.

Application September 22, 1937, Serial No. 165,156

2 Claims. (Cl. 259—160)

Our invention relates to improvements in concrete mixers.

Our invention relates to a device for handling materials and the concrete-forming mixture.

5 Our device is comprised primarily of a power driven vehicle having a concrete mixer mounted thereupon that is adapted for being power driven by the prime mover of the power driven vehicle.

Means is associated with one end of the power 10 driven vehicle for automatically lowering an inclined track leading from the ground to a sufficient height to permit a skip being moved thereover. When the skip is filled with aggregates, as sand, gravel, crushed rock, cement and cement 15 admixture the skip may be raised up the inclined track and be automatically dumped directly into a hopper that is in communication with the interior of the mixer.

After the aggregates have been delivered within 20 the hopper, a desired amount of the batch is then delivered into the mixer through the action of gravity and water is then admitted and the aggregates and water are then mixed in the mixing chamber of the mixer. A discharge opening 25 is disposed within one end of the mixer and a movable spout is adapted for being moved into and out of registry with the opening to facilitate the emptying of the mixer by means of unloading buckets inside the mixing chamber as the 30 same is power rotated.

Power means is provided for moving the chute into and out of registry with the discharge opening of the mixer. Manual means is provided for actuating the power means for operating the 35 chute.

Heretofore machines have been provided for carrying concrete aggregates from a central aggregate mixing plant to the point of distribution. Also portable mixers have been provided, but it is believed to be new in the concrete 40 mixer art to provide a mixer through the use of which concrete aggregates may be delivered into a skip and be delivered automatically through power means into the mixer, all of which are mounted upon a power driven truck that carries a tower that is in hinged relation with the truck frame in order that the complete mixer may be moved from job to job under its own power.

50 A tower is carried in conjunction with the truck that is adapted for being raised and lowered through the power means of the prime mover and an elevating bucket carried upon the mixer to elevate the mixed aggregates where high 55 structures are to be erected. The tower and

the bucket are carried upon the truck during portability of the mixer.

Our invention relates to improvements in concrete mixing instrumentalities where in our mixer the batch is power delivered as a batch, is 5 treated as a batch, and is elevated as a batch, with all power being supplied by the prime mover of the truck upon which the mixer is mounted. Our present machine is intended for use by contractors wherein the machine is made 10 to do the work in a more expeditious manner and whereby much time is saved and many of the operations now commonly performed by hand are eliminated. In our present machine the aggregate material is dumped from the delivery truck directly into a skip, as a batch of cement, sand and crushed aggregate, the batch is then elevated by the power of the prime mover of the truck, deposited into a receiving hopper at which point a predetermined amount of water 15 may be delivered simultaneously into the mixing drum of the mixer.

With these and incidental objects in view, the invention consists of certain novel features of construction and combination of parts, the essential elements of which are set forth in the appended claims, and a preferred form of embodiment which is hereinafter shown with reference to the drawings which accompany and form a part of this specification. 20 25 30

In the drawings:

Fig. I is a fragmentary side elevation of the assembled device. In this view the skip is shown in loading position in full line and in transporting position in dotted line. The tower is shown 35 in raised position in full line and in partially lowered position in dotted line.

Fig. II is a fragmentary side view of the assembled device. This view is made to illustrate the elevating tower and bucket with the bucket 40 in position for being loaded. The discharge chute is for delivering aggregate from the mixer into the loading bucket and to further illustrate the piping and operating cylinder for automatically actuating the discharge spout. 45

Fig. III is a fragmentary side view of the assembled device. In this view the loading skip is shown in two unloading positions, one being horizontal and the other being in partial elevation for depositing its unit of aggregate into the receiving hopper disposed therebelow. In this view the operating levers and instrumentalities are shown for placing the different units of the assembly in service when required. 50 55

Fig. IV is a fragmentary side view of the up- 55

per end of the inclined track over which the loading skip travels. The skip is shown in dumping position in full line and in unloading position in dotted line.

5 Like reference characters refer to like parts throughout the several views.

We have found satisfactory results to be obtained where our device is mounted upon a chassis supported upon four wheels and is driven 10 by a prime mover mounted within the chassis frame.

A pair of spur gears 24 and 25 are also mounted upon the shaft 18, and these respective spur gears 24 and 25 drive the mixing drum of the 15 concrete mixer hereinafter to be described.

The front of the chassis is supported by the conventional front wheels 33 and 34 that are steered in the usual and customary manner.

A concrete mixing drum 43 is provided. This 20 drum has turned bands 44 and 45 disposed about its outer periphery. These bands act as tires. A pair of trunnion wheels 46 and 47 are provided for each of the respective tires 44 and 45. The pair of trunnion wheels are mounted upon the 25 shafts 48 and 49 respectively and these shafts are journaled relative to the chassis in suitable journal bearings mounted within the respective cross supporting frame members.

Master gears 50 and 51 are disposed upon the 30 outside of the mixing drum and the same are preferably placed adjacent the tires 44 and 45, and the respective gears 24 and 25 mounted upon the power shaft coact with and drive the master gears 50 and 51 to impart rotation to the concrete mixing drum.

35 A superposed frame is provided being composed of longitudinal girders 52 and 53 and these are supported upon suitable posts 54, 55, 56, and 57 and in the larger units additional posts are provided. In order that the supporting posts may be tied together cross supports 58 and 59 are provided.

We have found that best results are to be obtained where the superposed frame members 45 consisting of longitudinal girders, posts, and other structural members are welded together.

In order that aggregate material may be delivered as required into the concrete mixing drum, we provide a receiving hopper 60 within 50 the superposed frame and a wheel supported skip 61 is provided as illustrated by the pairs of wheels 62 and 63.

A pair of spaced inclined fixed tracks 64 and 55 65, 66 and 67 are provided. It will be specifically noted that the respective pairs of wheel supports of the skip have different gage and the respective pairs of spaced tracks 64 and 65 have a wider gage than the tracks 66 and 67, so that the pair of wheels 62 moves upon the narrow 60 gage track at all times. Since the faces of the wheels 63 are relatively broad, they may ride upon the wide gage track or the narrow gage track with equal facility. The lower end of the primary tracks is comprised of hinged rails 68 65 and 69, and they are hinged together by suitable hinged pins 70 and 71. Hauling lines 72 and 73 are secured upon their one end to the outer or loading end of the skip, and these lines 72 and 73 are trained about suitable pulleys 74 70 and 75. The respective pulleys 74 and 75 are mounted upon a common shaft 76 that is journaled with the brackets that are secured to the posts 256 and 257 that are hingedly supported upon the superposed frame in conventional bearings.

The skip is shown in loading position in Fig. I with the inclined rails 68 and 69 of the track being in position to permit the skip to run thereover.

5 A stop notch 85 is provided adjacent the top end of each of the inclined rails 66 and 67. These stop notches are positioned to receive the back wheels 62 of the skip therein. The inclined rails 64 and 65 are positioned so that as the skip moves upwardly, the respective broad faces of the 10 wheels 63 will engage the inclined rails in advance of the wheel 62 engaging the stop notch 85. The dropping of the wheels 62 in the stop notches 85 prevents the further upward movement of the skip along the rails 67 and 68 and 15 the inclination of the skip caused by the broad wheels 63 engaging the rails 64 and 65 permits an upward tilting or upending of the skip to facilitate its load of aggregate being quickly dumped from the skip, and the same being dumped into 20 the aggregate receiving hopper 60.

We provide an end gate 86 within the discharge end of the skip. This arrangement is illustrated in Fig. III. The end gate is firmly held shut by a locking latch 86A and the locking latch has an arm 87 that outwardly extends from the end of the gate and when the tilting of the skip progresses sufficiently the arm 87 engages the splash plate 88 thus unlatching the latched end gate to thereby permit the contents of the skip to flow through the gate by gravitational action into the hopper 60 disposed therebelow. When the skip returns to its normal horizontal position, arm 87 disengages or leaves the splash plate 88 and the locking latch again 30 locks the end gate closed.

When it is desired to move the assembled mixer from one job to another, the skip is lowered and a locking hook 89 is hooked over the axle 90 and the skip is again pulled upward. In doing so the hinged rail 69 is hinged about the pin 71 and the further upward movement of the skip hinges the second hinged rail 68 about the hinge pin 70 to thereby place the two joints of hinged rails as shown in dotted position in Figs. I, II, and III. This places the skip and the track out of surface engagement with the ground and permits the movement of the same from one job to another and facilitates its being moved from one place to another. By moving the skip 50 further upward as illustrated in Fig. I the skip is moved out of view of the driver of the roadway over which the vehicle is to be driven.

The aggregate materials deposited within the hopper 60 are relatively dry, and the water 55 for the batch mix is admitted into the mixing drum simultaneously with the admitting of the batch of aggregates into the mixing drum. While the admission is made at about the same time that the aggregates are admitted into the mixing 60 drum, the actuator for admitting the water is independently and manually manipulated and controlled. The admission of the water into the water tank is automatically maintained full excepting at the discharge cycle.

A hydraulic cylinder 147 is provided. The hydraulic cylinder has a piston disposed therein to which is attached a piston rod 148, and an actuating bar 149 is hinged to the cylinder 147 and it normally rests against the outer end of the piston 70 rod 148. The piston rod 148 is forced outwardly by a spring disposed within the cylinder 147 and this spring maintains contact between the piston rod 148 and the actuating bar 149. As the torsional rod 142 is rotated in one direction, the ac- 75

tuating bar 149 is moved toward the cylinder 147 and operates the piston disposed within the cylinder and compresses the fluid disposed therein.

The tower 196 may run several stories above or below the level upon which the machine is stationed. For the purpose of this illustration and description, we have assumed that this tower is to be used for raising aggregates off the street's level, but it may be used with equal facility as a lowering device.

The tower is preferably fabricated from structural shapes and is reinforced and made heaviest at its lower end, as illustrated at 197.

Gusset plates 198 and 199 are placed upon the opposite sides of the tower to facilitate hingedly securing the tower to the superposed frame of the device. These gusset plates are bored to facilitate their being attached to and rotated about shafts 201 and 202.

When the tower 196 is to be erected, the hoisting bucket 221 is anchored to the base of the tower, and the line 219 is reeved about the sheave 222 and it is anchored or otherwise secured to the winding drum 20, and the winding drum is operated as hereinbefore described. Thus it will be noted that the same line for erecting the tower is used for hoisting the bucket within the tower. If the tower is to be used for relatively tall buildings, guy lines may be used in addition to the braces.

A plurality of braces 223 are used for supporting the tower above the structure. A plurality of braces 224 are used for supporting the tower at its base end. When the tower is to be lowered the braces 224 are detached and the braces 223 are released from the superposed structural frame at its lower end at which time the braces 223 may be used to initially move the tower in the direction that it is to be lowered. In order to facilitate this arrangement, each of the brake drums 22 and 23 is independently actuated.

The hoisting bucket 221 has slots 225 and 226 disposed within its opposite sides which are made to engage projections 227 and 228 disposed within the base of the tower, and when these projections are made to engage within the slots the bucket is tilted as illustrated in Fig. II in order that the mixed concrete from the hopper 157 may flow into the bucket.

In controlling the travel and operations of the skip 61 from the operator's platform 95, we provide a control shaft 214 that is journaled within suitable bearings 229, 230 and 231. An operating lever 232 is secured upon its one end to the control shaft 214 the connection being made by any suitable ball and socket joint 233.

A control rod 234 is provided. This rod is fastened upon its one end to a link 235.

We have heretofore in an earlier part of the specification described a skip that delivers aggregate from the forward end of the skip, but many times it is desired to deliver the aggregates from the skip at the rear end of the skip.

In Fig. IV, we have shown a slightly modified form of skip and means for actuating the same which permits of the dumping of aggregate from the rear end of the skip.

The primary purpose being to provide a skip that may be raised and lowered violently to thereby relieve the skip of any of its aggregates that have a tendency to cling to the inside of the skip body.

We provide uprights 256 and 257 and secure the same upon their lower ends to the top frame members 52 and 53. These uprights are braced by supporting members 258 that are secured upon their respective ends to the top frames 52 and 53 and to the shaft 76.

The hauling line is trained about suitable sheave blocks 259 and 260. The sheave blocks are mounted upon any suitable shaft 261. Tracks 262 are provided upon which the pair of wheels at the rear end of the truck rides, and a track 263 is provided upon which the front wheels of the skip ride.

A stop 264 is provided for stopping the forward movement of the skip when it assumes a horizontal position and the hauling line is secured to the front end of the skip and the same is trained about sheave blocks that are supported upon the respective uprights 256 and 257 so that when the skip is stopped in its forward movement through the action of the stop 264 the front end of the skip will then be raised and the front wheels of the skip will be made to engage the uprights 256 and 257 and the rear wheels 265 will ride upon the respective tracks 262. This will upend the skip. The skip has a rear end gate 267 and side walls 268. The upending of the skip trips the end gate and the aggregates flow from the skip into the hopper disposed therebelow.

A jolting of the skip may be effected by drawing the wheels 265 clear of the support and dropping the same violently on the track.

While the form of mechanism herein shown and described is admirably adapted to fulfill the objects primarily stated, it is to be understood that it is not intended to confine the invention to the embodiment herein shown and described, as it is susceptible of embodiment in various forms all coming within the scope of the claims which follow.

What we claim is:

1. In a device of the class described, the combination of a truck, said truck having a primary frame and a secondary frame with the secondary frame superposed on the primary frame, a jointed track secured to the primary and the secondary frames with said jointed track being adapted for being lowered and for resting upon the supporting surface of the ground when lowered, and for being raised at its jointed end and for being carried upon the truck when the truck is to be moved with power for said manipulation being supplied by the prime mover of the truck, and a skip having a pair of wheels disposed at each of its opposite ends adapted for being manipulated upon the track, and said skip adapted for being carried upon the track above its jointed ends when the truck is to be moved.

2. In a device of the class described, the combination of a truck having a concrete mixer mounted thereupon, an aggregate hoisting track disposed at the front end of the truck and said track passing over the engine and the cab of the truck and said track being hinged and adapted for being folded to afford portability to the truck with the track being carried by the truck when folded.

HAROLD A. WAGNER.
